CIGARETTE REST

Paul Keulman, Chicago, Ill.

Application June 10, 1954, Serial No. 38,909

Term of patent 14 years

(Cl. D85--2)

Fig. 3

Fig. 1

Fig. 4

Figure 4 is an end view.

The broken line showing of an ash tray in Fig. 1 is for illustrative purposes only. The stippled surface in Fig. 2 indicates a pressure responsive adhesive material.

I claim:

The ornamental design for a cigarette rest, substantially as shown and described.
